UNITED STATES PATENT OFFICE.

WILHELM SONNBERG, OF CHARLOTTENBURG, GERMANY, ASSIGNOR TO DEUTSCHE WAFFEN- UND MUNITIONSFABRIKEN, OF BERLIN, GERMANY.

MACHINE FOR FILLING CARTRIDGE-BELTS.

1,180,950.

Specification of Letters Patent. Patented Apr. 25, 1916.

Application filed July 6, 1912. Serial No. 708,070.

To all whom it may concern:

Be it known that I, WILHELM SONNBERG, engineer, a subject of the King of Prussia, residing at No. 14 Mindenerstrasse, Charlottenburg, near Berlin, Germany, have invented certain new and useful Improvements in Machines for Filling Cartridge-Belts, of which the following is a specification.

10 This invention has for its object an improved machine for filling cartridge belts, according to which the feed and adjustment of the belt are effected mainly by a pocket opening pin whereby greater exactitude in 15 the adjustment of the belt is obtained.

An embodiment of the invention is illustrated by way of example in the accompanying drawing, in which:

Figure 1 is a plan of the machine. Fig. 20 2 is a longitudinal section on the line 2—2 in Fig. 1, and Fig. 3 is a cross section on the line 3—3 in Fig. 1.

In a casing 1 a shaft 2 rotatable by means of a handle 9^a or in some other suitable manner is mounted and upon it a roller 3 is fixed. The roller 3 produces the reciprocating movement of the slide 8 parallel with the axis of the shaft 2 by means of a pin and roller 11 engaging a groove 12, and also 25 the rotation of the lever 13, pivoted to the casing 1 and terminating in a jaw 40, about its pivot 14 by means of the pin and roller 16, which engage in a groove 17 on the roller 3. The arm 18 of the second retaining lever 30 19, which is provided with a roller 21, is constantly held against the periphery of the roller 3 by means of a spring. The periphery of the roller 3 is tapered so that when the roller 21 rests on this tapered portion 35 the retaining lever 19 is rocked upward about its pivot 22 by this spring.

The shaft 2 also carries the cam plate 23 which acts on a roller 24 of a double slide 25 vertically displaceable in the casing 1; this slide is constantly drawn downward by 40 a spring 26 and its upper tapered end passes through an opening in the table 28.

The retaining levers and slides coöperate in such a manner that the slide 8 and the 45 retaining lever 19 on the one hand and the slide 25 and the retaining lever 13 on the other hand temporarily hold the belt 41 between them or release it.

On the right hand end of the shaft 2 the crank 29 is mounted which by means of a connecting rod 30 engages a slide 32 which is horizontally displaceable beneath the table 28 in the casing 1. This slide 32 reciprocates at right angles to the axis of the shaft and supports the pin 33 serving for opening and spreading out the pockets in the belt and also the cartridge slide 34. The cartridge slide removes the cartridge which for the time being is the lowest in a reservoir and inserts it into the pocket opened by the pin 33.

The pin 33 is fixed in a slide 36 which is displaceably mounted on the slide 32 parallel with the axis of the shaft and in an arm 37 of the slide 8 at right angles to this direction. The pin 33 is therefore displaced by the slide 8 parallel with the axis of the shaft and by the slide 32 perpendicularly thereto.

The cartridge slide 34 is mounted on the slide 32 with a limited capacity for movement parallel with the axis of the shaft and is constantly pressed outward by a spring 39. It is also acted upon by a guide lever 43 which temporarily holds it in the right hand end position.

The machine operates as follows: Proceeding from the position of the machine illustrated in the drawing when the crank 9^a is rotated the pocket opening pin 33 penetrates the pocket tightly stretched between the grippers and is simultaneously moved forward in the feed direction together with the grippers 8, 19. As soon as the pin has reached the front grippers 13, 25 they move upward and downward so that the pin and the grippers 8, 19, conjointly are able to displace the belt until the pin reaches the place previously assumed by the cartridge last inserted in the belt. The lever 13 then again descends and simultaneously the double slide 25 moves upward so that the belt is held on the two intermediate walls between the pocket to be filled while the pin is withdrawn and a cartridge is inserted into this pocket by means of the cartridge slide 34. After the pin 33 has left the pocket the grippers 8, 19, the latter in the raised position, move back and the pin returns to its initial position.

What we claim and desire to secure by Letters Patent of the United States is:

1. In a machine for filling cartridge belts, belt feeding means adapted to grip the belt, and means adapted to open the pockets in the belt and also to displace the belt in the direction of feed.
2. In a machine for filling cartridge belts, belt feeding means adapted to clamp the belt between them and pocket opening means adapted in conjunction with said feeding means to displace the belt in the direction of feed.
3. In a machine for filling cartridge belts, means adapted to clamp the belt between them at both sides of a belt pocket, and means adapted to open the belt pockets, said clamping means and said pocket opening means operating in conjunction to feed the belt.
4. In a machine for filling cartridge belts, means adapted to clamp the belt between them, means adapted to open the belt pockets, and means adapted to displace said clamping means and said pocket opening means in the direction of feed.
5. In a machine for filling cartridge belts, means adapted to open the belt pockets and also to displace the belt in the direction of feed, and means adapted to clamp the belt between them at both sides of a pocket during the opening of same.
6. In a machine for filling cartridge belts, means adapted to open the belt pockets and also to displace the belt in the direction of feed, means adapted to introduce cartridges into the pockets, and means adapted to clamp the belt between them at both sides of a pocket during the introduction of a cartridge into same.
7. In a machine for filling cartridge belts, means adapted to open the belt pockets and also to displace the belt in the direction of feed, means adapted to introduce cartridges into the belt pockets, and means adapted to clamp the belt between them at both sides of a pocket during the opening of same and during the introduction of a cartridge into same.
8. In a machine for filling cartridge belts, reciprocating pocket opening means adapted to displace the belt in the direction of feed, and means adapted to clamp the belt between them at both sides of the opened pocket during the idle return movement of said pocket opening means.
9. In a machine for filling cartridge belts, reciprocating pocket opening means adapted to displace the belt in the direction of feed, means to introduce cartridges into the belt pockets, and means adapted to clamp the belt between them at both sides of a pocket during the insertion of a cartridge into said pocket and during the idle return stroke of said pocket opening means.
10. A machine for filling cartridge belts comprising a plurality of grippers adapted to clamp the belt between them and a pocket opening pin, said grippers and said pin co-operating to feed the belt.
11. In a machine for filling cartridge belts, a pair of grippers and a pocket opening pin both adapted to reciprocate in the direction of feed and to displace the belt in this direction, and a second pair of grippers adapted to clamp the belt between them during the idle return stroke of said first pair of grippers and of said pocket opening pin.
12. In a machine for filling cartridge belts, a slide, means for reciprocating said slide in the direction of feed, a lever pivoted to said slide and adapted to press the belt upon said slide during its forward stroke, a pocket opening pin, means for reciprocating said pin in a direction toward the belt, and means for reciprocating said pin in the direction of feed.
13. In a machine for filling cartridge belts, a slide, means for reciprocating said slide in the direction of feed, a lever pivoted to said slide and adapted to press the belt on said slide during its forward stroke, a second slide, a stationary member, a lever pivoted to said stationary member and adapted to coact with said second slide to clamp the belt between them, a pocket opening pin, means for reciprocating said pin in a direction toward the belt, and means for reciprocating said pin in the direction of feed.
14. A machine for filling cartridge belts comprising a slide, a pair of grippers one member of which is pivotally mounted on said slide and adapted to grip the cartridge belt, a second pair of grippers the members of which are movable in a direction at right angles to the direction of feed and having jaws thereon for embracing the last cartridge pocket that has been filled.
15. A machine for filling cartridge belts comprising a slide having one end formed with a gripping surface, a gripping member pivotally mounted on said slide, a stationary member, a second pair of grippers one member of which is pivoted to said stationary member, the other member being formed as a slide and adapted to coact with said pivot member to hold the cartridge belt while the pockets therein are being filled, and a pocket opening pin movable in a direction toward said pockets and also in the direction of feed for the purpose of assisting to effect the feed of said belt.
16. A machine for filling cartridge belts comprising a slide having one end formed with a gripping surface, a gripping member pivotally mounted on said slide, a stationary member, a second pair of grippers one member of which is pivoted to said stationary member and having a jaw formed on its free extremity, the other member being formed as a double slide and adapted to coact with

said jaw of said pivoted member to hold the cartridge belt at both sides of a pocket while this pocket is being filled, and a pocket opening pin movable in a direction toward said 5 pockets and also in the direction of the feed for the purpose of assisting to effect the movements of said belt.

In testimony whereof I have affixed my signature in presence of two witnesses.

WILHELM SONNBERG.
